UNITED STATES PATENT OFFICE.

JOHN MUSCO VALLEY AND BARLOW MARCOTTE, OF CHICAGO, ILLINOIS.

SPARK-PLUG FOR EXPLOSIVE-ENGINES.

1,320,810.

Specification of Letters Patent.

Patented Nov. 4, 1919.

Application filed May 29, 1919. Serial No. 300,572.

To all whom it may concern:

Be it known that we, JOHN MUSCO VALLEY and BARLOW MARCOTTE, citizens of the United States, and residents of Chicago, in the county of Cook and State of Illinois, have jointly invented certain new and useful Improvements in Spark-Plugs for Explosive-Engines; and we do hereby declare that the following description of our invention, taken in connection with the accompanying sheet of drawings, forms a full, clear, and exact specification, which will enable others skilled in the art to which the said invention appertains to make and use the same.

This invention has general reference to spark plugs for igniting the explosive charges in internal combustion engines; and it consists, essentially in the novel and peculiar combination of parts and details of construction, as hereinafter first fully set forth and described, and then pointed out in the claims.

The object of this invention is the production of an efficient, serviceable, and comparatively inexpensive spark plug, which can be readily applied to, and removed from, the motor for cleaning and renewal purposes. Other objects of this invention will hereinafter appear.

In the drawings forming a part of this specification—Figure 1 is an elevation of this spark plug. Fig. 2 is a longitudinal sectional elevation of the same.

A, in these drawings designates the metallic, main body of this spark plug. It is preferably, of hexagonal contour, to permit of the application of a suitable wrench, as shown in the figures at 12, the lower portion of which body is reduced in diameter, as at 13, and externally screw-threaded, as at 14, to the conventional size and number of threads to the inch, to fit into, and engage the openings in the engine cylinders, tapped to receive the same. The upper end of this main body A is, likewise, reduced in diameter, as at 15, which reduced portion is externally screw-threaded to receive a recessed nut B.

The main body A is longitudinally bored, as at 16, which bore is reduced in diameter at its lower end to afford a shoulder 17, thereat, while the upper end of this bore is enlarged, as at 18, which latter portion thereby affords a second shoulder 19, in said bore, the enlargement 18 and the interior of the nut B being filled with packing C,

preferably of asbestos or other non-combustible, but somewhat elastic, material.

In the bore 16, and projecting from both ends of the body A, there is located a core D, of vitreous material, such as glass, porcelain, and the like. This core is centrally and longitudinally bored throughout, to receive a metallic electrode E, which electrode is long enough to protect from both ends of said core, its upper end being externally screw-threaded to engage a cap F, located at the upper end of the core D, and project therefrom to receive a thumb, or binding, nut 20, which connects one end of an electric conductor 21, to the electrode E.

The core D has within the enlarged bore 18 of the main body A an annular collar 22, which bears upon the shoulder 19 aforesaid; and spaced therefrom there is near the lower end of said core D, a second collar 23, which bears upon the shoulder 17 at the lower end of the bore 16. Beneath this collar there is, preferably placed an elastic, non-combustible washer 24.

From the lower end of the body A extends a second electrode G, which is in metallic contact with the body A, which latter body, when installed in an engine cylinder, forms one of the two poles of an electric circuit. This second electrode has its free end bent at right angles, and as shown in the figures of the drawings, this end reaches to within a predetermined distance of the lower end of the electrode E, either at the side thereof, as illustrated in Fig. 1, or a predetermined distance below the same, as indicated at 25, in Fig. 2, to afford the required spark gap, either construction being effective and perfectly satisfactory.

While we prefer the direct connection of the electric conductor to the electrode E, as shown in Fig. 2, we may modify this construction by employing a spring-jack 26, of usual construction. This element 26, as shown in Fig. 1, is pushed over the neck 27, formed in the cap F, and carries a binding post 28, by which the electric conductor 21 is secured to the jack 26.

It may now be noted that there is in the body A a wide space between the interior wall of the body A and the exterior of the core D, or, in other words, the bore 16 in the body A is considerably larger in diameter than the diameter of the core D, which prevents possible 110 contacting with each other. The coefficient of expansion of the body A is slightly

greater than that of the core D, so that, in view of the fact that the body A expands longitudinally in upward and downward directions, but mostly upwardly, because the 5 lower end of the body is fixedly connected to the engine cylinder, this slight upward movement will have a tendency to slightly lift the core by its collar 22, not enough, however, to endanger this collar and cause 10 it to snap off the main portion of the core. This lifting of the core will cause a very slight upward movement of the collar 23 from the shoulder 17, and thereby prevent any possible damage to said collar by the 15 expansive force of the parts. At the same time, the elastic washer 24 below the collar 23 prevents oil, grease, or carbon to enter the space 16, so that fouling is practically eliminated. Any carbon collecting at the 20 terminals of the electrodes can be readily removed in the usual manner.

Having thus fully described our invention, we claim as new, and desire to secure by Letters Patent of the United States—

- 25 1. A spark plug for explosive engines and the like, comprising, in combination, a metallic main body, said body having a longitudinal axial bore throughout, the lower end of said bore being contracted to afford a shoulder thereat, the upper end of said bore being enlarged to afford a second shoulder in said metallic body, both of said shoulders being in the same upward direction, a core of vitreous material in said bore, said core 30 being round and of the same diameter throughout, said core being considerably smaller in diameter than the bore in said main body, there being on said core approximately medially of its length, an annular 35 collar, constructed to bear upon the shoulder in the enlarged bore, there being on said core near its lower end a second annular collar constructed to bear upon the shoulder formed by the contracted portion of said 40 bore, said core being integrally formed with said collars, said core having an axial bore throughout its entire length, an electrode in the latter bore, said electrode projecting from both ends of said core, the upper end of said 45 electrode being externally screw-threaded, a clamping nut on said screw-threaded portion, a metallic cap at the upper end of said core to which said electrode is fixedly connected, an electric conductor secured to said cap by said 50 clamping nut, a second electrode in metallic contact with said main body and reaching within a predetermined distance of the lower terminal of said first-mentioned electrode to afford a spark gap therebetween, there being at the upper end of said metallic body a reduced, externally screw-threaded portion, a recessed nut in engagement with said latter portion, a non-combustible elastic packing in said nut and said enlarged bore and bearing upon the upper face of the first-mentioned collar, and an elastic, non-combustible washer between the lower face of the second-mentioned collar and the shoulder at the lower end of said bore in the main body.

ing within a predetermined distance of the lower end of said first-mentioned electrode to afford a spark gap between said electrodes.

- 55 2. A spark plug for explosive engines and the like, comprising, in combination, a main, metallic body, said body having an axial bore throughout, the lower end of said bore being contracted to afford a shoulder thereat, the upper end of said bore being enlarged to afford a second shoulder near the upper end of main bore, both of said shoulders facing in an upward direction, a core of vitreous material in said bore, said core 60 being round and of the same diameter throughout, said core being considerably smaller than the bore of said main body, there being on said core approximately medially of its length, an annular collar located 65 in the enlarged space of the main body and bearing upon the shoulder therein, there being on said core near its lower end a second annular collar fitting the bore of said main body and bearing upon the shoulder formed 70 by the contraction of said bore, said core being integrally formed with said collars, said core having an axial bore throughout its length, an electrode in the latter bore, said electrode projecting from both ends of said 75 core, the upper end of said electrode being externally screw-threaded, a clamping nut on said screw-threaded portion, a metallic cap at the upper end of said core to which said electrode is fixedly connected, an electric conductor secured to said cap by said 80 clamping nut, a second electrode in metallic contact with said main body and reaching within a predetermined distance of the lower terminal of said first-mentioned electrode to afford a spark gap therebetween, there being at the upper end of said metallic body a reduced, externally screw-threaded portion, a recessed nut in engagement with said latter portion, a non-combustible elastic 85 packing in said nut and said enlarged bore and bearing upon the upper face of the first-mentioned collar, and an elastic, non-combustible washer between the lower face of the second-mentioned collar and the shoulder at the lower end of said bore in the main body.

In testimony that we claim the foregoing as our joint invention, we have hereunto set our hands.

JOHN MUSCO VALLEY.
BARLOW MARCOTTE.
